UNITED STATES PATENT OFFICE.

THOMAS H. GRADY, OF CHICAGO, ILLINOIS, ASSIGNOR TO CRUVER M'F'G CO., OF CHICAGO,
ILLINOIS, A CORPORATION OF ILLINOIS.

BADGE OR BUTTON.

1,334,239.

Specification of Letters Patent. Patented Mar. 16, 1920.

Application filed February 23, 1918, Serial No. 218,727. Renewed February 2, 1920. Serial No. 355,699.

To all whom it may concern:

Be it known that I, THOMAS H. GRADY, citizen of the United States, residing at Chicago, in the county of Cook and State of Illinois, have invented certain new and useful Improvements in Badges or Buttons; and I do hereby declare the following to be a full, clear, and exact description of the invention, such as will enable others skilled 10 in the art to which it appertains to make and use the same.

This invention relates to improvements in buttons or badges, and more particularly to devices of this kind which are adapted to 15 be secured to the clothing by means of a hinged bar pin having its hinge connection with the back of the badge or button at one side of the same and engaging at its point in a recess therein at the opposite side 20 thereof.

The invention relates more particularly to the specific type of badge or button which includes a back plate or member which is dished to provide a peripheral flaring flange 25 or bead which is provided at one side with a substantially horse-shoe shaped recess constituting a catch to engage the point of the bar pin for securing the same against opening.

The present invention has for its particular object to provide means for more securely engaging the point of the pin against accidental release, and consists in the features of construction and combinations of 35 parts hereinafter fully described and claimed.

In the accompanying drawings illustrating the preferred embodiments of the invention:

Figure 1— is a rear view of a badge or button constructed in accordance with my invention.

Fig. 2— is a vertical sectional view of the same on the line 2—2 of Fig. 1—.

Figs. 3— and 4— are detail fragmentary perspective views of the same.

Fig. 5— is a view similar to Figs. 3— and 4— showing a modified embodiment of the invention.

As shown in the accompanying drawings, the back plate A of the badge or button which, in the instance illustrated is elliptical, is provided with an annular flaring flange of ogee-curved cross-sectional shape. 55 This flange is provided at diametrically op-

posite points with an opening C through which the shank of the fastening pin D extends and is provided at a diametrically opposite point with a C-shaped opening E so made as to provide a tongue F which is 60 bordered by a recess G and a recess H of respectively different depths. The tongue G is disposed at an incline and lies in the plane of the inner inclined portion of the flange B. The depth of the recess E is such that its 65 outer or endmost portion is disposed at a distance from the pivot of the pin D slightly greater than the extreme length of said pin so that, as the point of the pin is depressed, it will pass through said recess and may 70 then be turned laterally to pass under the free end of the tongue F and into the shorter recess H. The end wall of the latter is disposed sufficiently nearer the pivot of the pin 75 so that the point of the latter will project beyond the end of said recess H and thus be engaged to prevent accidental release.

It has been found in practice, however, that the pins vary slightly in length, and that, furthermore, the bottoms or extreme 80 ends of the recesses G and H may not be sufficiently separated from each other to provide for the projection of the point of the pin beyond the end wall of the recess H a sufficient distance to at all times prevent 85 said point from being released by accidentally bowing the pin.

The object of the present invention is, therefore, to provide means for more securely engaging the point portion of the pin 90 against accidental release, and consists in providing at the side of the opening E which constitutes a continuation of one side of the recess H an overhanging hook I underneath which the point portion of the pin 95 passes simultaneously with the passing of the extreme point portion underneath and past the tongue F and into the recess H. The said tongue I is formed by utilizing a portion of the metal which is cut out of the 100 plate A in forming the opening E and consists in leaving a tongue of metal extending from the side of the opening E which is flush with the outer side wall of the recess H and which is struck up and bent over at 105 its free end to form the overhanging loop or hook I in a well-known manner.

It will be seen from the foregoing that my invention provides not only a very firm 110 engaging means for the point portion of the

pin, but also provides means for disposing the extreme point of the pin out of harm's way.

The invention may also be carried out as shown in Fig. —5— by providing the usual horse-shoe shaped opening in the flange to provide the tongue F bordered by the recesses G and H, and cutting out of the body of the plate A contiguous to said opening 5 a tongue J which is struck up and has its free end turned over to provide the overhanging loop or hook K engaging the pin contiguous to the point portion thereof a little nearer the pivot than in the case of 10 the tongue I, shown in Figs. —1— to —4— 15 inclusive.

While I have shown the preferred embodiments of the invention in the accompanying drawings, it will be understood, of course, that the same may be changed and varied in immaterial details without departing from the invention as defined in the appended claims.

I claim as my invention:

25 1. In a badge equipped with a bar-pin and having a flaring peripheral flange provided with a C-shaped slot having a long and a short portion arranged relatively to the pivotal axis of the pin to permit the point of 30 the latter to pass through the long portion of said slot at one side and retain the same engaged with the said flange when moved laterally to engage in the short portion of 35 said slot, an inverted hook disposed contiguous to the last-named portion of said slot and adapted to engage the pin contiguous to and inwardly of the point thereof for pre-

venting accidental opening movement of said pin from the shorter portion of said slot by bowing the pin.

2. A badge equipped with a flexible bar-pin and having an annular flaring flange, a slot in said flange having a long portion through which the point of said pin is adapted to pass when flexed and having a 45 short portion in which the point portion of said pin is adapted to be received and engaged when moved laterally after passing through the longer portion of said opening, a projection bordering the last-named side 50 of said opening and having a bent over free end portion presenting an inverted hook overhanging the shorter portion of said slot and adapted to engage the pin inwardly of the point thereof when the latter is engaged 55 in the shorter portion of said slot.

3. A badge equipped with a flexible bar-pin and having an annular flaring flange, a slot in said flange having a long portion through which the point of said pin is 60 adapted to pass when flexed and having a short portion in which the point portion of said pin is adapted to be received to engage underneath said flange when the point portion of said pin is moved laterally after 65 passing through the longer portion of said slot, and a projection presenting an inverted hook disposed contiguous to the shorter portion 70 of said slot for engaging the point portion of the pin at a distance from the point thereof simultaneously with the engagement of said point portion underneath the said flange.

THOMAS H. GRADY.
